UNITED STATES PATENT OFFICE.

ROBERT L. HUNTER, OF CLEVELAND, OHIO.

CARD-INDEX.

SPECIFICATION forming part of Letters Patent No. 718,630, dated January 20, 1903.

Original application filed January 10, 1901, Serial No. 42,749. Divided and this application filed November 21, 1901. Serial No. 83,170. (No model.)

To all whom it may concern:

Be it known that I, ROBERT L. HUNTER, a citizen of the United States, residing at Cleveland, county of Cuyahoga, State of Ohio, have invented certain new and useful Improvements in Card-Indexes, of which the following is a specification.

My invention relates to improvements in the boxes or trays for card-indexes or catalogues, and has particular reference to the provision of an expansible locking or retaining member for securing the cards in the box or tray and which may be readily applied to the common form of box or tray or removed therefrom.

Expansible locking devices for card-indexes as heretofore constructed have necessitated either a deep cut in the cards or a complicated operation of the locking device when inserting and removing cards from the box or tray.

The object of my invention is to provide an expansible locking or retaining means which necessitates but shallow cuts or slots in the index-cards and at the same time requires but a simple manipulation, as by the turning of a thumb-nut, to operate the same.

A further object of my invention is to so arrange the parts of the expansible locking or retaining device that they shall be self-contained and adapted for ready application to and removal from the common form of box or tray.

Further purposes and advantages of my invention and the details thereof will be more definitely pointed out in the following description, and the invention will be further defined in the accompanying claims.

The invention will be more readily understood by reference to the accompanying drawings, forming part of this specification, and in which—

Figure 1 is a perspective view showing my invention applied to a common form of card box or tray, the side of the latter being shown broken away. Fig. 2 is a plan view showing the expansible locking or retaining device, the upper part being broken away to more clearly show the locking-strips. Fig. 3 is a longitudinal vertical section showing the position of the operating mechanism of the lock-

ing or retaining device in the box or tray. Fig. 4 is an enlarged transverse section on lines 4 4 of Fig. 2. Fig. 5 is an enlarged transverse section on line 5 5 of Fig. 2. Fig. 55 6 is an enlarged transverse section on line 6 6 of Fig. 2. Fig. 7 is a perspective view showing the connection between the returning-spring and a locking-strip. Fig. 8 is a perspective view of the front end of the locking 60 or retaining device, showing the operating mechanism therefor. Fig. 9 illustrates, on an enlarged scale, a latch for securing the locking or retaining device in the box or tray. Figs. 10 and 11 are longitudinal and trans- 65 verse sections, respectively, of the follower.

As shown in the drawings, 2 represents a box or tray of the usual preferred form, having grooves 3 near the bottoms of the longitudinal sides for the reception of lugs or projections 4 at the ends of follower 5. For holding the follower in position behind the cards I provide two spring-pressed plungers 6 in vertical sockets near the face of the follower 70 nearest the cards. The bottom of the follower is padded with cloth or felt, through which the plungers exert force upon the bottom of the box or tray, tending to tilt the follower and causing projections 4 to cramp in the grooves 3. In the middle of the bottom edge of the follower I provide a rectangular recess 7, having notches 8 near the upper part thereof for the free passage of the card locking or retaining device 9. The locking or retaining device 9 comprises a bar 85 10, preferably of greater width than height, provided with narrow longitudinal grooves 11 in its opposite sides for the reception of the locking strips or blades 12. The grooves 11 are located as near the top of bar 10 as 90 possible, so that the locking strips or blades 12, carried therein, when projected may engage notches 8 of the follower, near the top of the recesses in the same. The blades or strips 95 12 are provided with cam-slots 13 and ride upon and are held by cam pins or nails 14. The blades or strips 12 are usually projected, as shown in Figs. 2, 4, 5, and 6, being maintained in this position by the action of springs 100 15, located in a recess in the bottom of bar 10. These springs have their ends respec-

tively attached to a transverse pin 16 in the bar 10 and to curled lugs struck from the metal blades or strips 12. It is obvious that if the blades or strips 12 are drawn forward 5 they will be contracted or drawn within the bar 10 by the operation of the cam-slots 13 and pins 14 and free the cards held thereby. To draw these blades or strips forward, I provide a sliding plate 17 in the forward end of the bar 10 and connect the same with the blades or strips 12 by means of pins 18, carried by said plate, which engage in transverse slots 19 in the ends of the blades or strips 12. The plate 17 is bifurcated, as shown in Figs. 2 and 15 8, to straddle the solid middle part of bar 10 between the grooves 11. The plate 17 is provided with a sleeve 20, accommodated by a notch 21 in the forward end of bar 10. The sleeve 20 contains a pin or feather 22, which 20 engages a spiral groove 23 in the revoluble stem 24 of the thumb-nut 25, and when the thumb-nut is turned the sleeve 20, plate 17, and the strips or blades 12 will be drawn forward by the action of the spiral groove on the 25 pin or feather 22. I prefer to use a yoke 26 on the forward end of bar 10 to furnish a bearing for the forward end of the operating-stem of the thumb-nut and to hold the same in place when the bar is removed from the box 30 or tray. The near end of the operating-stem is provided with a small pivot 27 to hold the same in place relative to the end of the bar 10. To permit the easy insertion or removal 35 of the bar 10 and parts connected thereto, I make an aperture 28 in the forward end of the box or tray, and this aperture is normally closed by a latch or plate 29, pivoted at one end upon a screw or pin, and having a notch at its other end to engage a screw or pin. At 40 the middle of plate 29 I provide a notch 30 to receive the operating-stem 24 and lock the bar 10 in position after the same has been inserted in the box or tray. The rear end of the bar is held in position by the follower or, 45 if desired, it may be secured by a screw.

It is obvious that my locking or retaining device may be made a permanent fixture of the card box or tray, and in such case the hole 28 will only be of a size to admit the operating-shank, and the plate 29 may be dispensed with. It is also obvious that my invention admits of various modifications that will readily suggest themselves to one skilled in the art, and I accordingly do not confine my 55 invention to the specific construction herein shown and described.

This is a divisional application, the subject-matter having been first described and claimed in my pending application, entitled 60 "Cross-index," Serial No. 42,749, filed January 10, 1901.

Having thus described my invention, what I claim as new, and desire to secure by Letters Patent, is—

65 1. The combination of a tray or box with an expansible card locking or retaining device in the bottom thereof and comprising a

grooved bar, locking strips or blades having cam-slots and slidably in the grooves of said bar, cam-pins in said bar and means for moving said strips or blades longitudinally to project the same or retract them in said grooves, substantially as described. 70

2. A card locking or retaining device comprising a grooved bar, locking strips or blades 75 adapted to enter said grooves, means for moving said strips or blades longitudinally, consisting of a thumb-nut having a spirally-grooved stem, a sleeved plate adapted to engage said stem and said strips or blades and 80 means for moving said strips or blades toward and from each other as they are moved longitudinally, substantially as described.

3. The combination with a box or tray of a bar 10 provided in the bottom thereof and 85 having grooves 11 in its sides, the strips or blades 12 slidable in said grooves and having cam-slots, cam-pins in said bar and means for operating said strips or blades to project the same or retract them into their grooves, 90 substantially as described.

4. The combination with a box or tray of a bar 10 in the bottom thereof, expanding strips 95 or blades slidable in and normally projecting from the sides of said bar, the returning-springs 15 and means for positively operating and retracting said strips or blades within the outline of the bar, substantially as described.

5. The combination with the box or tray of 100 the bar 10 provided with the slidable and retractable strips or blades 12, the sliding plate to which said strips or blades are connected, the sleeve and the spiral cam-stem in said sleeve, whereby said sliding parts are operable, substantially as described. 105

6. The combination of a box or tray with a bar 10 of greater width than height and provided with longitudinal grooves in its sides, strips or blades slidable in said grooves and 110 means for positively moving said strips or blades toward and from each other and projecting them from said grooves or retracting the same therein, substantially as described.

7. The combination with a box or tray, having 115 grooves 3 in its sides, of the follower 5 provided with lugs or projections 4 and having a cloth-padded bottom and the spring-actuated plungers 6 contained in said follower, substantially as described. 120

8. The combination with a box or tray, of a follower 5 slidably engaging the sides of said box or tray and provided with a cloth-padded bottom and spring-actuated plungers 6 adapted to bear upon said cloth bottom and tilt the 125 said follower, substantially as described.

In testimony whereof I have hereunto set my hand, in the presence of two witnesses, this 20th day of August, 1901.

ROBERT L. HUNTER.
